CLAIM

The ornamental design for a face panel with advertising frames for a coin telephone box, as shown and described.

DESCRIPTION

FIG. 1 is a front elevation view of a face panel with advertising frames for a coin telephone box showing my new design with the box and its coin return and coin storage sections, and the telephone transmitter-receiver instrument and cord shown in phantom outline;

FIG. 2 is a rear elevation view thereof;

FIG. 3 is a side elevation view thereof, the opposite side being a mirror image; and,

FIG. 4 is a bottom view thereof, the top view being a mirror image.

The broken line showings of FIG. 1 are for illustrative purposes only and form no part of the claimed design.
